M. L. DODGE,
SHOE AND METHOD OF MAKING THE SAME,
APPLICATION FILED NOV. 6, 1916.

1,221,154.

Patented Apr. 3, 1917.

UNITED STATES PATENT OFFICE.

MILTON L. DODGE, OF NEWBURYPORT, MASSACHUSETTS.

SHOE AND METHOD OF MAKING THE SAME.

1,221,154.

Specification of Letters Patent.

Patented Apr. 3, 1917.

Application filed November 6, 1916. Serial No. 129,659.

To all whom it may concern:

Be it known that I, MILTON L. DODGE, a citizen of the United States, and resident of Newburyport, in the county of Essex and State of Massachusetts, have invented certain new and useful Improvements in Shoes and Methods of Making the Same, of which the following is a specification.

This invention relates to shoes, and particularly to the stiffening members used therein. It is customary to use separate elements for stiffening the counter portion and shank portion of a shoe, but my present invention contemplates a counter stiffener which, if long enough, will materially reinforce the shank of the sole without the use of a special shank stiffener. However, a special shank stiffener may also be used if it is desired to stiffen the shank to a greater degree than that possible with the counter stiffener alone.

The characteristic feature of the counter stiffener is that portions of its heel-seat flange are lapped, one over the other. In order to utilize the lapped portions of the flange to stiffen the sole, I fasten them directly to the sole by fastening means anchored in the latter. If the lapped portions extend a considerable distance in front of the breast of the heel and are anchored directly to the shank portion of the sole, the latter is stiffened to such degree that some shoes would not require any additional shank-stiffening means. However, it is possible to utilize a special shank stiffener in conjunction with the lapped portions of such flange, and the drawings show a shoe in which both stiffeners are incorporated.

A defect that is found in the majority of shoes is that the forward extremities of the counter stiffener spread one from another and enable the shank portion of the upper to bulge, the result being an inferior fitting and unsightly shoe. This defect exists to a greater degree in low shoes than in high shoes, and is particularly difficult to overcome in low shoes. A shoe made in accordance with my present invention would not have the defect described, provided the forward portions of the counter stiffener are arranged in the desired relation when they are fastened to each other.

As far as the fundamental principle of the invention is concerned, the fastening of the forward portions of the counter stiffener one to another, and the anchoring of such

portions to the shank portion of the sole, are capable of being performed in turn shoes and in shoes that are not turned, such as welt shoes and McKay shoes. I have illustrated a turn shoe in the process of being made according to this invention. In my copending application, Serial No. 116,331, filed August 22, 1916, I have disclosed a method of making turn shoes in which the forward extremities of a counter stiffener are anchored directly to the sole of a turned shoe. In that case the flange of the counter stiffener is not lapped, and the forward portions are anchored to the sole separately, so that the flange does not afford so great a shank-stiffening effect as it does according to the present invention, in which the flange of the counter stiffener is lapped where it is anchored to the sole.

If an additional shank stiffener is used it may extend to the heel end of the counter stiffener, and its heel-seat portion may have an outline that conforms substantially to the crease that defines the junction between the heel-seat flange and upstanding portion of the counter stiffener. The shank stiffener would be arranged to lie between the foot and the flange of the counter stiffener, so that it would provide a smoother tread surface for the foot than would be the case if it were omitted. The shank stiffener may extend further forward than the counter stiffener.

Of the accompanying drawings, which illustrate the present invention as embodied in a turn shoe and in a welt shoe:

Figure 1 represents a top plan view of a shoe that has been lasted and sewn wrong side out, and to the sole of which have been secured a counter stiffener and a shank stiffener. According to the condition of the shoe the latter is ready to be turned right side out.

Fig. 2 represents a vertical cross section through the shoe, in the plane indicated by line 2-2 of Fig. 1, the figure including a jack or anvil adapted to sustain the shoe while the metallic fastener is upset to anchor the extremities of the counter stiffener, and the shank stiffener, to the sole.

Fig. 3 represents a longitudinal section through that portion of the shoe intersected by line 3-3 of Fig. 1, omitting the jack or anvil.

Fig. 4 represents a vertical cross section through the heel portion of the shoe after

the latter has been turned, replaced upon the last, and provided with the usual heel-seat nails.

Fig. 5 represents a vertical cross section through that portion of the turned shoe corresponding to line 2—2 of Fig. 1, the shoe being in the same condition as in Fig. 4.

Fig. 6 represents a vertical cross section through a welt shoe in a plane corresponding to line 2—2 of Fig. 1, such shoe including a counter stiffener and shank stiffener anchored directly to the sole by a metallic fastener extending therethrough.

Fig. 7 represents a side elevation of a finished shoe made in accordance with this invention, the shank portion of the sole being stiffened by the lapped forward ends of the counter stiffener and by an additional stiffening member, which are fastened directly to the sole in front of the breast of the heel.

The same reference characters indicate the same parts wherever they occur.

The sole, upper, lining and inseam stitches are indicated at 10, 11, 12 and 13 respectively. The shoe according to Fig. 1 has been lasted wrong side out, and the lining is outside the upper. In the present instance the stitches 13 extend around the heel-seat portion of the shoe, under the counter stiffener, and the pulled-over marginal portion of the upper is secured to the sole by such stitches. The lining, throughout the shank portion and forepart, is also secured by the stitches 13, but the counter portion 12' of the lining is left free, so that it may be tucked into the counter stiffener after the shoe has been turned, all of which is in accordance with the method disclosed in my aforesaid copending application. In order to leave the counter portion 12' of the lining free such portion is snipped transversely, as indicated at 12^x, 12^x, at points in line with the extremities of the counter stiffener.

45 The counter stiffener is indicated at 14, and its heel-seat flange is indicated at 15. The forward portions of said flange are relatively wide and are arranged in lapped relation, as shown best by Fig. 2, the lapped 50 portions having sufficient area to receive one or more fasteners such as that indicated at 16. A fastener of any suitable form may be used, that shown in the present instance being a rivet split at one end to provide 55 tongues or spurs 17, 17. When such a fastener is used it is preferable to insert it from the bottom face of the sole, so that the tongues or spurs 17 will be upon the inside of the shoe. If a shank stiffener such as that 60 indicated at 18 is to be used it is arranged upon the flange of the counter stiffener prior to inserting the fastener 16, and the latter is then driven through the sole, through the 65 lapped portions of the flange, and through the shank stiffener, and the tongues or spurs

17 are then bent outwardly away from each other and hammered down and clenched upon the shank stiffener, as shown by Fig. 2. For this purpose the shoe may be placed upon a jack or anvil 19 after the fastener 70 has been inserted but before the tongues or spurs have been hammered down. The bulk of material as shown by the drawings is slightly exaggerated, as it would be difficult to illustrate the elements clearly if the elements were shown as thin as they would actually be.

When the shoe has progressed to the stage represented by Figs. 1 and 2 it is ready to be turned right side out, and in the course 80 of turning it the counter portion 12' of the lining would be carried up over the upper edge of the counter stiffener and then tucked down into the latter as represented in Figs. 4 and 5. Cement or other adhesive substance 85 may be applied to the inner face of the counter stiffener or to the contacting face of the lining to hold the latter securely in place. When this has been done the last 20, may be replaced in the shoe preparatory to inserting 90 the heel-seat nails 21. When the said nails are driven they pass through the sole, through the flange 15 of the counter stiffener, through the heel-seat portion of the shank stiffener 18, through the margin of 95 the counter portion 12' of the lining, and are turned back and clenched by the usual metal plate 22 on the last. This having been done the shoe is ready to be beaten out and otherwise prepared for the reception of a heel. 100

Although I have described a turn shoe and a method of making the same, the invention, as far as it relates to the finished article, is capable of being embodied in a shoe that is made right side out, such as a 105 welt shoe or a McKay shoe, in which case also the lapped portions of the counter stiffener and the shank stiffener would be secured directly to the sole by a fastener 16.

I claim:

1. In the art of making turn shoes, the method comprising the steps of lasting the shoe and securing the pulled-over portion of the upper to the sole, securing directly to the sole, and right side up, a stiff molded 115 counter stiffener that has a heel-seat flange, by arranging the forward extremities of such flange in lapped relation and driving a fastener through the sole and through such lapped portions of the flange, turning the 120 shoe, and otherwise securing the counter stiffener by driving fasteners through the heel-seat margin of the sole and through said flange.

2. In the art of making turn shoes, the 125 method comprising the steps of lasting the shoe and securing the pulled-over portion of the upper to the sole, arranging, right side up on the sole, a stiff molded counter stiffener that has a heel-seat flange, lapping the for- 130

ward extremities of such flange, arranging a shank-stiffener so as to overlie such lapped portions of the flange, driving a fastener through the sole, through such lapped portions, and through said shank-stiffener, turning the shoe, and driving nails through the heel-seat margin of the sole, through said flange, and through said shank-stiffener.

3. A shoe comprising a sole, an upper, a counter stiffener having a heel-seat flange the forward extremities of which are lapped, one over the other, and a fastener extending through such lapped portions of said flange and being anchored in said sole, whereby the forward portions of said counter stiffener are secured directly to the sole.

4. A shoe comprising a sole, an upper, a counter stiffener having a heel-seat flange the forward extremities of which are lapped, one over the other, a shank stiffener, and a fastener extending through such lapped portions of said flange, and through said shank-stiffener, and being anchored in said sole, whereby said shank-stiffener and the forward portions of said counter stiffener are secured directly to the sole and to each other.

5. A shoe having a counter stiffener therein, said counter stiffener having a heel-seat

flange the forward portions of which are lapped one over the other, and fastening means extending through said lapped portions to secure the forward portions of the stiffener against spreading.

6. A shoe having a counter stiffener therein, a heel, the forward ends of said counter stiffener being lapped one over the other in front of the breast of the heel, and fastening means anchored in the sole in front of the breast of the heel and extending through such lapped portions of the counter stiffener.

7. A shoe having a counter stiffener therein, a heel, a shank-stiffener, and fastening means anchored in the sole in front of the breast of the heel and extending through said shank stiffener, the forward portions of said counter stiffener being between said shank stiffener and the sole, and being a substantial distance in front of the breast of the heel, said fastening means extending through said counter stiffener.

8. A shoe having a counter stiffener the forward ends of which have lapped portions fastened directly to each other.

In testimony whereof I have affixed my signature.

MILTON L. DODGE.
